UNITED STATES PATENT OFFICE.

PARKE P. FLOURNOY, OF BETHESDA, MARYLAND.

DEVICE FOR FILLING FOUNTAIN-PENS.

1,290,534.

Specification of Letters Patent.

Patented Jan. 7, 1919.

Application filed October 22, 1917. Serial No. 197,770.

To all whom it may concern:

Be it known that I, PARKE P. FLOURNOY, a citizen of the United States, residing at Bethesda, in the county of Montgomery and State of Maryland, have invented certain new and useful Improvements in Devices for Filling Fountain-Pens, of which the following is a specification.

My invention relates to means which may be quickly and easily applied to all the existing forms of fountain pens, and fill or replenish the writing fluid within the barrel of the pen.

The objects of my invention are for the purpose of forming a device of the character above indicated, and is intended to form a means by which a fountain pen reservoir may be filled without unscrewing and separating the feeding attachment in which the pen point is fastened from the ink reservoir or barrel of the pen, and also without removing the pen point from the feeder or reversing the ink stand or other container from which the ink is to be withdrawn and forced into the barrel or reservoir of the fountain pen.

The invention consists of structural characteristics and relative arrangements of elements which will be hereinafter more fully described and particularly pointed out in the appended claims.

In the one sheet of drawing in which similar reference characters indicate the same parts in the several figures:

Figure 1 is a side elevation of the device embracing my invention;

Fig. 2, is a longitudinal vertical section of the device applied to the neck of an ink container and showing in elevation the relation of a fountain pen point when used in connection with the device, and

Fig. 3 is a section on line III—III of Fig. 2.

Referring to the drawings *a* is a hollow compressible rubber bulb which is provided with an extension or mouth piece *b*, also of rubber and provided with an outwardly tapered conical or flaring opening *b'* adapted to tightly and firmly receive the usual conical end of the pen point end of a fountain pen, as shown in Fig. 2. The inner walls of the cavity within the bulb *a* and next to the opening *b'* are flared outwardly for the purpose of preventing the pen point of the pen *C*, see Fig. 2, from coming in contact with the interior

of the bulb *a*, and hence giving no chance for said pen point *C* thus to become injured.

Attached to and preferably integrally formed with the bulb *a* is a base section or stopper *d* which is adapted to fit snugly and tightly within the neck of a bottle *B* or any container for ink, as shown in Fig. 2, and is provided with a flange *h* capable of firmly seating itself on the top of the mouth of said bottle *B*. Depending from and connected with the outer or lower end of the base section or stopper *d* is a tube *e* which communicates by means of a passage *e'* within the stopper *d*, with the interior of the bulb *a*, and the lower end *g* of said tube *e*, is cut off diagonally, as shown for the purpose of permitting both ink and air to flow freely through said tube *e*, and passage *e'* when the bulb *a* is manipulated in filling the fountain pen to be hereinafter described. Said bulb *a* is arranged in order to bring the axis of its hollow interior in such a position and in a plane substantially normal to the axis of the internal passage *e'*, so that the ink remaining in the bulb after the pen has been filled, as will be presently described, will gravitate or flow back into the bottle *B*. On the outer side and near its upper end of the base section or stopper *d* which is adapted to fit within the neck of the bottle or container *B* is formed an encircling annular recess *i*, and a series of separated trenches or depressions *f*, *f*, extending from the said recess *i* to the lower or tube end of the stopper *d*, for the purposes to be presently described.

The operation of the invention is as follows:

The pen point *C* having been securely and tightly fastened into the flaring opening *b'*, as shown in Fig. 2, the stopper *d* is raised out of the opening in the neck of the ink container or bottle *B*, until the annular recess *i* is in communication with the outside air. If the bulb *a* is now compressed, a portion of the air in it is forced through the passage *e'* and tube *e*, down through the ink in the container *B*, and emerges from the ink, an equal amount of air escaping by way of the depressions *f*, *f*, and recess *i*, to the atmosphere. When the bulb *a* is released from pressure and allowed to expand, some of the air within the hollow pen barrel is drawn out, and some of the ink in the container or bottle *B* is drawn up to fill the vacuum formed in the bulb *a* by its expansion. This operation of compressing and releasing the

bulb *a* is repeated, drawing up more ink and expelling more air from the pen barrel, and the pen point *C* being slightly depressed below the horizontal position, the ink will 5 pass down into the pen barrel to fill the increasingly perfect vacuum therein, while the air being lighter than the ink rises and passes into the hollow bulb *a*, and is eventually by repeated compressing and releasing 10 of the bulb, forced as previously explained through the passage *e'* and tube *e* and up through the ink, and finally escapes into the atmosphere by the vents or depressions *f*, *f*, and recess *i*, until the pen barrel 15 is entirely filled with ink, and the gurgling sound produced by the passage of the outgoing air through the ink ceases, indicating that the filling of the pen is completed. After this operation and after the withdrawal 20 of the pen from the mouth piece *b*, the pen is ready for use.

The object of providing an annular recess *i*, with a series of depressions *f*, is for the purpose of sub-dividing and distributing the 25 outgoing air entirely around the stopper *d* and prevent any great air pressure at any one depression or vent *f*, which would tend to squirt or force out suddenly any ink which might lodge or collect, if a single depression *f* were employed. The recess *i*, extends 30 entirely around the stopper *d* and of a depth as shown for the purpose of acting as a reservoir to receive any ink which might be forced through the depressions or vents *f*, 35 thereby preventing any ink from being thrown out from the stopper or bottle during the compression of bulb *b* and filling of the pen barrel *A*.

From the foregoing disclosure of the construction and operation of the device, it will 40 be seen that all of the advantages and func-

tions set up in the statement of invention are fully carried out, and it will also be understood that many modifications will readily suggest themselves without departing 45 from the spirit and essential features of my improvements.

What I claim is:

1. A device for filling fountain pens comprising a base section provided with external 50 trenches formed therein and having a single internal passage, a tube having its upper end attached to said base section and communicating with one end of said internal passage and its lower end adapted to pass below the 55 surface of the writing fluid, a hollow compressible bulb secured to said base section having its interior in communication with the open end of the internal passage opposite to that which is in communication with said tube and provided with an extension having an opening adapted to snugly and tightly receive the pen point end of a fountain pen. 60

2. A device for filling fountain pens comprising a base section provided with a single 65 external annular recess and a series of trenches normal to and communicating with said recess and having an internal passage, a tube having its upper end attached to said 70 base and communicating with one end of said internal passage and its lower end adapted to pass below the surface of the writing fluid, a hollow compressible bulb secured to said base section having its interior in communication with the open end of the internal passage opposite to that 75 which is in communication with said tube and provided with an extension having an opening adapted to snugly and tightly receive the pen point end of a fountain pen. 80

PARKE P. FLOURNOY.
